UNITED STATES PATENT OFFICE.

JOHN S. BERRY, OF TYLER, TEXAS, ASSIGNOR OF TWO-THIRDS TO WILLIAM QUINN AND MORRIS DOWLER, OF SAME PLACE.

GATE-LATCH.

SPECIFICATION forming part of Letters Patent No. 574,517, dated January 5, 1897.

Application filed April 24, 1896. Serial No. 588,899. (No model.)

To all whom it may concern:

Be it known that I, JOHN S. BERRY, a citizen of the United States, residing at Tyler, in the county of Smith and State of Texas, have 5 invented certain new and useful Improvements in Gate-Latches; and I do hereby declare the following to be a full, clear, and exact description of the invention, such as will enable others skilled in the art to which it 10 appertains to make and use the same.

My invention relates to gate-latches; and it consists in the details of construction hereinafter described and claimed.

In the accompanying drawings, Figure 1 is 15 a side elevation of my invention. Figs. 2 and 3 are detail views.

My invention is described as follows:

A is the gate-post.

B is the latch-post.

20 C is a hinged beam.

D is the latch-beam, and E are the slats and braces.

In the latch-beam D is secured a latch-pin 25 d, and to the latch-post B is pivoted a latch e. Through the latch-post B runs a hollow cylinder e, which is rigidly secured in place, and through this hollow cylinder works a rod e², to the front end of which is rigidly secured the latch e, said rod being rigidly secured in 30 the perforation e³ of said latch.

To the outer end of the rod e² is rigidly secured an arm e⁴, to the free end of which is secured a weight e⁵. Said latch e is provided with inclines e⁶ and a recess e⁷, and just below the said latch and secured in the face of 35 the post B are pins e⁸. These pins are intended as stops to keep the latch from turning too far.

The operation of the gate is so apparent that I deem it unnecessary to describe the 40 operation.

Having described my invention, what I claim as new, and desire to secure by Letters Patent, is—

The combination with a gate, of the beam 45 D, provided with the latch-pin d; perforated post B; rod e², working in said post; arm e⁴, secured on the outer edge of rod e²; latch e, having the inclines e⁶ and recess e⁷, rigidly secured to the inner end of the rod e²; stop- 50 pins e⁸, secured in the face of the post B, substantially as shown and described and for the purposes set forth.

In testimony whereof I affix my signature in presence of two witnesses.

JOHN S. BERRY.
